E. A. Losee

UNITED STATES PATENT OFFICE.

EZRA A. LOSEE, OF LAKE CITY, IOWA.

POULTRY-FOUNTAIN.

SPECIFICATION forming part of Letters Patent No. 664,959, dated January 1, 1901.

Application filed May 29, 1900. Serial No. 18,477. (No model.)

To all whom it may concern:

Be it known that I, EZRA A. LOSEE, a citizen of the United States, residing at Lake City, in the county of Calhoun and State of Iowa, have invented certain new and useful Improvements in Poultry-Fountains; and I do hereby declare the following to be a full, clear, and exact description of the invention, such as will enable others skilled in the art to which it appertains to make and use the same.

My invention relates to improvements in poultry-fountains for feeding water to poultry and swine automatically when attached to a water-supply barrel or tank.

My object is to provide a novel and improved poultry-fountain that is light, simple, cheap, durable, portable, and easily attached to a water-supply barrel or tank.

A further object is to provide an improved form of poultry-fountain having a long low drinking-space in front and a high covered float-chamber in the rear.

In the accompanying drawings, Figure 1 is a perspective view of my poultry-fountain, showing means for attaching to a water-supply barrel or tank. Fig. 2 is a perspective view of the interior of my poultry-fountain and valve mechanism.

The numeral 1 designates a metal cup having the front wall lower than the back wall and part of the side walls lower than the main side walls, with an aperture in the back wall.

The numeral 5 designates a hollow valve-seat (elbow shape) projecting from the base seat and carrying post extensions to fulcrum the float-lever to.

The numeral 6 designates a valve fastened to the under side of one end of the float-lever 7, and 8 is a metallic float fastened to the opposite end of said lever, which is fulcrumed between the post extensions.

The numeral 4 designates a valve-seat base bolted to the back wall of cup 1 and to waste-nut opposite, with water-tight gaskets between 4 and 1 and 2 and 1 opposite the aperture in the back wall.

The numeral 2 designates a waste-nut carrying a nipple, gaskets, and lock-nut, said waste-nut being bolted to the back wall of 1

and base of valve-seat and opposite the aperture in the back wall.

The numeral 3 designates a cap sliding in grooves on the inside of the end walls and adjustably fastened to the top of the back-wall.

The operation is obvious and as follows: 55 When the fountain is attached to a water-supply barrel or tank, the water passes through the nipple, through the aperture in the back wall of the cup, and through the hollow valve-seat and base into the cup until the 60 water raises the float and closes the valve tight against the valve-seat. When the float is down, the water runs freely. When the float is level, the water ceases to run. The float rides on the water, following the water up 65 and down, and controls the valve and supply of water from the barrel to the cup.

There are many slight and immaterial changes of construction which might be resorted to in carrying out my invention, and 70 hence it is to be understood that I do not limit myself to the precise construction herein shown and described, but consider that I am entitled to all such variations as come within the spirit and scope of the invention. 75

Having thus described my invention, what I claim as new, and desire to secure by Letters Patent, is—

1. In an automatic poultry-fountain, a metallic cup having the front wall lower than the back wall, and part of the side walls lower than the main side walls, an aperture in the back wall, a valve-base bolted to the front of the back wall, opposite the aperture, and carrying an elbow-shaped valve-seat, with post extensions, a lever fulcrumed between the post extensions, a valve fastened to one end of the lever, and a float fastened to the opposite end of said lever.

2. In a device of the class described, a metallic cup having the front wall lower than the back wall, and part of the side walls lower than the main side walls, an aperture in the back wall, a valve-seat base bolted to the front of the back wall, opposite the aperture, and carrying an elbow-shaped valve-seat with post extensions, a lever fulcrumed between the post extensions, a valve fastened to one end of the

lever, and a float fastened to the opposite end of said lever, a waste-nut carrying a nipple, gaskets, and lock-nut, bolted to the rear of the back wall; and valve-seat base, water-
5 tight gaskets between, and all opposite the aperture in the back wall; a cap to protect the valve mechanism, resting in grooves on the

inside of the side walls, and adjustably fastened to the top of the back wall.

EZRA A. LOSEE.
